UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 5, 1922. Serial No. 604,975.

To all whom it may concern:

Be it known that I, SAMUEL B. WILLIAMS, a citizen of the United States, residing at Brooklyn, in the county of Kings and State 5 of New York, have invented certain new and useful Improvements in Telephone-Exchange Systems, of which the following is a full, clear, concise, and exact description.

This invention relates to telephone exchange systems and more particularly to exchange systems employing automatic switching and controlling apparatus for building up conversational connections.

The object of the invention is an improved 15 system of the character wherein talking connections are established partly through the agency of manually operated equipment and partly through the medium of machine switching apparatus.

20 A feature of the invention relates to an arrangement wherein a switch controlling register sender is connected to any one of a number of circuits outgoing from an operator's position responsive to the operator's act 25 of making connection with such circuit.

Another feature relates to the provision of 30 an arrangement wherein connecting circuits outgoing from a plurality of operators' positions appear in a single coordinate switch, which serves to extend said circuits over the trunks of a group outgoing from such switch.

A further feature relates to a register sender, arranged for connection with trunks 35 outgoing from the operator's position when she makes connection with such trunks, adapted to transmit a record over the trunk to a distant controlling mechanism by means of code impulses.

40 A still further feature relates to an improved overflow arrangement whereby any operator may appropriate for use the connecting circuits at other operators' positions.

45 Other and further features contemplated in this invention will become apparent from the detailed description given hereinafter and also from the appended claims.

Referring to the drawing, Figs. 1 to 7, inclusive, when arranged in the order shown 50 in Fig. 9, disclose a telephone exchange system incorporating the features of the invention.

Fig. 1 shows a subscriber's line terminating 55 before an operator in a manual office and

also one of the operator's cord circuits. Below the horizontal broken line this figure also illustrates two connecting circuits outgoing from the particular operator's position at which the cord circuit shown is located. Above the horizontal broken line is shown a connecting circuit appearing at another operator's position.

Figs. 2, 3 and 4 illustrate a register sender device associated with the operator's position illustrated in full in Fig. 1. Fig. 2 shows certain controlling relays and circuits. Fig. 3 at the left shows the operator's key set consisting of ten non-locking keys. At the right of this figure is shown the first of 70 a series of four relay registers. Fig. 4 shows the remaining three relay registers of the series.

Fig. 5 shows one of a number of coordinate switches which serves to connect the connecting circuits leading from a plurality of operators' positions to a group of trunks outgoing to a distant mechanical office.

Fig. 6 illustrates a distant mechanical office in which the automatic switches, diagrammatically shown, serve to extend the incoming trunk to a called subscriber's line. Also, this figure shows in the space at the left and above the broken line, a sender selecting switch and certain controlling relays and elements associated with the first of the group selecting switches. In the space below and to the right of the broken line there is shown the receiving portion of the register controlling mechanism.

Fig. 7 shows the relay second registers of the register controlling mechanism.

Fig. 8 is a schematic diagram showing the relative arrangement of the various parts of the system.

Consulting Fig. 8, a manual office is here represented by two of a number of operators' positions 800 and 810. Calls are received at the operators' positions in any well-known manner and are answered by the operators through the use of cord circuits, such as the cord 801 located at position 800 and cord 837 located at position 810.

Outgoing from the operator's position 800 there are a number of groups of connecting circuits, one group for each distant mechanical office to which this particular operator may have access. Circuits 802 and 803 are two of a group over which the operator at position 800 may establish connections to the

100

105

110

distant mechanical office 825. Similarly circuits 804 and 805 are two of a second group over which the operator may establish connections with the distant mechanical office 835. Circuits 802, 803, 804 and 805 appear at the position in the regular jacks 806, 807, 808 and 809 and also in the overflow jacks, respectively, 811, 812, 813 and 814. Circuits 802 and 803 extend from the operator's position and appear in the vertical row of the coordinate switch 820.

Switch 820 serves to extend connections to the mechanical office 825. Consequently there appear in this switch the connecting circuits leading from each of a plurality of the operators' positions. Circuits 802 and 803 appearing in this switch come from the operator's position 800. Circuits 838 and 839 are two of a group appearing before 20 the second operator's position 810 and which also lead to an incoming vertical row of the coordinate switch 820. Similarly, other groups of circuits at other operators' positions may appear in the switch 820 for connection with the distant mechanical office 825. Outgoing from the switch 820 is a group of inter-office trunks of suitable size, three of which, trunks 821, 822 and 823, are shown. In the manner to be explained 25 hereinafter, the connecting circuits leading from the operators' position to the switch 820 are connected to the outgoing trunks through the medium of links 824, 826, 827 and 828.

Also associated with the operator's position 800 is a register sender controlling device 815. The sender 815 is common to all circuits of all groups outgoing from the operator's position and may be associated 40 with any one of said circuits in response to the act by the operator of inserting one of her plugs in the regular jack of such outgoing circuit. The operator by means of the key set sets up a numerical record on 45 the sender which later transmits code impulses over the selected trunk circuit to the distant mechanical office there to establish a corresponding record on a second register controlling device.

The coordinate switch 830 is similar to the switch 820 and serves to extend connections from the operator's positions over a group of inter-office trunks to the distant mechanical office 835. For instance, the circuits 804 55 and 805 of the second group at the operator's position 800 appear in the switch 830 and are extended thereby to the distant office 835. Similarly, corresponding groups of circuits leading from other operators' positions appear in the switch 830 for a similar purpose.

The operator's position 810 is also equipped with a sender 829 which corresponds to the sender 815,

65 Should the operator at any position, as,

for example, the operator at position 800, find busy all connecting circuits in a desired group outgoing from her position, she may appropriate for use a circuit in the corresponding group at an adjacent position 70 provided there is an idle one. To do this the operator at position 800 inserts the overflow plug 816 into the overflow jack 838 of the idle circuit 838 at the adjacent position 810. The act of inserting the overflow plug 75 in the overflow jack renders the connecting circuit non-connectible to the sender 829 at the position 810 and connects it instead to the sender 815. In this way any operator 80 may use the connecting circuits outgoing from another position in order to route calls to a given distant mechanical office when all of the corresponding circuits at her own position are in use.

The coordinate switches illustrated in Fig. 85 8 diagrammatically, and shown in detail as the switch 500 in Fig. 5, may be of the same general character as the switch described in detail in the British patent No. 183,438, issued to Western Electric Company, Limited, accepted September 6, 1923.

A specific description will now be given 90 explaining the manner in which the system operates when a connection is extended from the subscriber's line 100, which is assumed to terminate in the operator's position 105 of the manual office illustrated in Fig. 1, to the subscriber's line 633 terminating in the distant mechanical office. When the subscriber of line 100 initiates a call, the 100 operator responds in the usual manner by inserting the plug 104 of an idle cord circuit 101 in the jack 103. The operator converses with the calling subscriber in the usual manner and obtains from him orally 105 the name of the desired office and the number of the called subscriber's line therein. Having received this information and knowing that the call is one for the particular mechanical office illustrated in Fig. 6, the 110 operator seizes the plug 106 and notes if there is an idle connecting circuit of the particular group over which the connection may be routed to the required mechanical office. Finding that the connecting circuit 108 of 115 the proper group is idle, the operator inserts plug 106 into the regular jack 111 of said circuit.

The insertion of the plug 106 into jack 111 completes a circuit from battery through 120 the winding of relay 107, sleeve of plug 106, sleeve of jack 111, winding of relay 121 to ground. Relay 121 operates and closes a circuit from battery through the winding of relay 516, conductor 132, outer right contact of relay 119, left back contact of relay 120, left contact of relay 121, lower back contact of relay 122, conductor 137, winding of relay 202, contact of relay 203 to ground. Relays 516 and 202 operate in this circuit. 125

Relay 516 serves to initiate the operation of the coordinate switch 500 for the purpose of extending the connecting circuit 108 through an idle link 505, 506, etc., to an outgoing trunk 509, 510, etc., leading to the distant mechanical office. The connecting circuit 108 is seen to appear in the vertical row of contacts 501 together with the other connecting circuit 109 leading from the same operator's position. A second vertical row of contacts 502 is illustrated in which connecting circuits 511 and 524 appear incoming from the same or another operator's position. Only two trunks 509 and 510 occupying respectively the complete vertical rows 504 and 503 are shown, although there may be as many as necessary.

When the relay 516 operates, it closes a circuit from battery through the winding of the vertical operating magnet 518 individual to the row 501, conductor 525, inner right contact of relay 516 to ground at the left contact of one or more of the horizontal operating magnets 512, 513, etc. The magnet 518 prepares the contacts in the vertical row 501 and also establishes a circuit from ground through its inner right contact, conductor 526, innermost left back contact of vertical magnet 520, inner left front contact of relay 527 (assuming the trunk 510 to be busy), conductor 528, outer left contact of relay 523 (assuming the trunk 509 to be idle), winding of vertical operating magnet 521 to battery. Magnet 521 rotates the associated rod and prepares the contacts in the row 504. Magnet 521 completes a circuit from ground through its middle contact, winding of slow-to-release relay 523 to battery. Relay 523 operates immediately and closes a circuit from ground through its right contact, inner left back contact of slow-to-operate relay 522, winding of relay 522 to battery. Relay 522 being slow to energize does not attract its armatures for an appreciable interval of time after the closure of its circuit. Relay 523 in operating opens the original energizing circuit of magnet 521. Magnet 521, however, remains energized in a substitute circuit traceable as follows: battery, through the winding of said magnet, outer left back contact of relay 522, innermost front contact of magnet 521, conductor 528, thence to ground at the inner right contact of magnet 518. This holding circuit of magnet 521 is maintained during the interval that relay 522 remains deenergized, which is sufficient to allow the operation of one of the horizontal link magnets 512, 513 to establish the connection through the switch 500.

Immediately that magnet 521 operates and before relay 522 has time to energize, a circuit is closed from ground through the outermost left contact of magnet 521, con-

ductor 528, left contact of magnet 518, conductor 529, outer right back contact of relay 517, outer right front contact of relay 516, normal contact and winding of horizontal link magnet 512 to battery, assuming the link 505 to be idle at this time. Magnet 512 rotates the associated bar and establishes connection from the circuit 108 through the link 505 to the idle trunk 509. Magnet 512 in operating extends the start wire through its outer right contact to the winding of the next link magnet 513. When magnet 512 operates it closes a temporary holding circuit for itself as follows: battery, through the winding and inner right front contact of said magnet, sleeve conductor 530 of link 505, contacts of switch 500 in the row 504, conductor 531, inner left back contact of relay 522, right contact of relay 523 to ground. The operation of the switch 500 also establishes a circuit from battery through the winding of relay 120, sleeve conductor 131, through contacts of the switch 500 by way of link 505, thence over conductor 531 to ground at the right contact of relay 523. Relay 120 operates and locks through its winding and right contact to ground at the right contact of relay 121.

After the necessary interval has elapsed following the closure of the circuit of relay 522, said relay attracts its armatures and in so doing opens the holding circuit of the vertical magnet 521. Magnet 521 restores the associated rod to its normal position and also opens the circuit of relay 523. Relay 523, however, remains energized in a circuit from battery through its winding, inner left front contact of relay 522, conductor 531, thence as traced through contacts of the switch 500, over conductor 131, right contact of relay 120 to ground at the right contact of relay 121.

Relay 522, in operating, also opens the temporary holding circuit of the horizontal magnet 512. Magnet 512, however, is held energized in a circuit from battery through its winding and inner right contact, contacts of the switch 500 in row 501, sleeve conductor 131 to ground at the right contact of relay 121. The maintained operation of relay 523 extends the starter wire 538 through the inner left back contact of magnet 521 and the inner left front contact of relay 523 to the next trunk.

Relay 522, in operating, opens its original energizing circuit but this relay is maintained energized in a circuit from battery through its winding, thence over conductor 531, through contacts of the switch 500 as traced, to ground at the right contact of relay 121.

When relay 120 attracts its armatures it opens the circuit traced for relay 516. Relay 516 in releasing opens the circuit of

70

75

80

85

90

100

105

110

115

120

125

130

the vertical magnet 518. Magnet 518 restores the associated rod and the connection is now held by the sole energization of the horizontal magnet 512. Relay 516 in releasing extends the starter wire 529 through to the corresponding relay at the next group of horizontal link circuits.

When relay 120 first operates it opens, as explained, the holding circuit of relay 516. 10 Relay 516, however, being slow-to-release maintains its armatures attracted for a definite interval thereafter. While relay 516 is remaining operated after the energization of relay 120, a circuit is closed from battery 15 through the winding of relay 119, conductor 133, left contact of relay 516, conductor 134, left front contact of relay 120, left contact of relay 121, lower back contact of relay 122, conductor 137, winding of relay 202 to 20 ground at the contact of relay 203. Relay 119 operates and immediately locks through its inner right contact to ground over the circuit just traced. Relay 119, at its left contacts, opens the tip and ring conductors 25 of the talking circuit 108 and connects said circuit to the register sender shown in Figs. 2, 3 and 4.

The operator on receiving the numerical designation of the called subscriber's line 30 proceeds at once to write the number on the single set of keys 300 at her position. To do this the operator depresses in succession four keys, each representing a digit in said number. Assuming the designation of the 35 wanted line is 1246, the operator depresses first the No. 1 key 314, then the No. 2 key 315, then the No. 4 key 316 and lastly the No. 6 key 317.

The operation of key 314 establishes a circuit from ground through the right contacts of said key, conductor 318, thence in parallel through the winding of relay 319 and through the lower back contacts of relays 301 and 302 and the winding of relay 303 45 to battery. Relays 319 and 303 operate. Relay 319 in operating closes a locking circuit for itself from battery through its winding and contact to ground at the upper contact of relay 301. Relay 319 also closes a locking 50 circuit for relay 303 traceable through the contact of relay 319 to the ground at the upper contact of relay 301. These locking circuits for relays 319 and 303 are seen to be independent of the original circuits closed 55 by the key 314. Hence, the key 314, if immediately released, does not cause relays 319 and 303 to become deenergized. These relays will only release after the registration 60 has been fully recorded on the register 310. 65 Relay 303, in operating, closes a circuit from battery through its winding and left contact, thence over conductor 320, winding of relay 301, contact of relay 319, to ground at the upper contact of relay 301. Relay 301 does not energize at this time since its winding

is shunted by the energizing circuit for relay 303, above traced.

When the key 314 is operated a circuit is also closed from ground through the left contacts of said key, conductor 321, conductor 322, winding of relay 323 to battery. Relay 323 operates and locks through its contact to ground at the upper contact of relay 301. As soon thereafter as relay 303 operates, a circuit is established from ground 70 through the upper contact of relay 301, conductor 324, contact of relay 323, conductor 322, conductor 321, next to the innermost right contact of relay 303, winding of register relay 304 to battery. Relay 304 operates 75 and closes a circuit from battery through the winding of relay 302, conductor 326, outermost left contact of relay 304, conductor 327, conductor 324, to ground at the upper contact of relay 301. Immediately 80 that relay 302 operates it opens the shunt around the winding of relay 301 and this latter relay operates in series with relay 303. If the operator has not yet released the key 314 the operating circuit of relay 301 may be 85 traced as follows: battery, through the winding and left contact of relay 303, conductor 320, winding of relay 301, conductor 318, contact of key 314 to ground. If the operator has released the key, however, the operating circuit of relay 301 may be traced 90 through the contact of relay 319, to ground at the upper back contact of relay 301. In either event the relay 301 attracts its armatures and in so doing removes ground from 95 conductor 324, whereby relays 303, 301, 319 and 323 become deenergized as soon as key 314 is released, provided this key has not already been released by the operator. Relay 302 remains energized in a circuit from 100 battery through its winding and inner upper contact, conductor 329, conductor 330, contact of relay 202, to ground at the contact of relay 203. Relay 304 also locks in a circuit from battery through its winding and 105 inner left contact, thence over conductor 329, to ground at the contact of relay 203.

When the operator depresses the next key 315, a circuit is closed from ground through the right contacts of said key, conductor 115 318, over a parallel circuit one branch of which extends through the winding of relay 319 and the other branch through the lower contact of relay 301, lower front contact of relay 302, conductor 332, lower back 120 contact of relay 400, winding of relay 401 to battery. Relay 319 operates and closes a circuit from battery through the winding and left contact of relay 401, conductor 320, winding of relay 301, contact of relay 319, to ground at the upper contact of relay 301. Relay 301, being shunted by the direct circuit from battery through the winding of relay 401 to ground, does not operate at 125 this time. Another circuit is closed from 130

ground through the left contact of key 315, conductor 333, winding of relay 334 to battery. Relay 334 operates and locks through its contact over conductor 324, to ground at the upper contact of relay 301.

When relay 401 operates, a circuit is closed from ground through the contact of relay 334, conductor 333, middle right contact of relay 401, winding of register relay 10 403 to battery. Relay 403 operates and locks through its inner left front contact, conductor 426, conductor 427, conductor 330, thence to ground at the contact of relay 203.

Relay 403 also closes a circuit from battery 15 through the winding of relay 400, conductor 428, outer left contact of relay 403, conductor 429, conductor 324, to ground at the upper contact of relay 301. Relay 400 operates and locks through its inner upper contact to

20 the grounded conductor 426. Relay 400 opens the shunt around relay 301 and this relay energizes in series with relay 401. Relay 301 removes ground from conductor 324, whereupon relays 319, 301, 334 and 401 25 become deenergized, provided the key 315 has been released by the operator.

When the operator depresses the next key 316, a circuit is closed from ground through the right contacts of said key, conductor 318, 30 330 thence over a parallel circuit, one branch of which leads through the winding of relay 319 and the other branch through the lower contact of relay 301, lower front contact of relay 302, conductor 332, lower front contact 35 of relay 400, lower back contact of relay 408, winding of relay 409 to battery. Relay 409 operates and in a manner similar to that already described completes a circuit for itself in series with the winding of relay 301. Relay 301, however, being shunted does not operate at this time.

The depression of key 316 also establishes a circuit from ground through the left contacts of said key, conductor 335, winding of relay 336 to battery. Relay 336 operates and locks through grounded conductor 324. As soon as relay 409 operates a circuit is closed from ground over conductor 324 through the contacts of relay 336, conductor 335, next to 45 the outermost right contact of relay 409, winding of register relay 413 to battery. Relay 413 operates and locks through its inner left contact, conductor 431, to ground over conductor 427. Relay 413 closes a circuit from battery through the winding of relay 408, conductor 432, outer left contact of relay 413, conductor 433, conductor 324 to ground. Relay 408 locks in a circuit from battery through its winding and inner upper contact, to ground over conductors 431 and 427. Relay 408 at its lower back contact 50 opens the shunt around relay 301 and this relay operates to in turn cause the deenergization of relays 336, 319, 301 and 409 in 55 the manner above explained.

Lastly, when the operator depresses the key 317 for the units digit of the wanted number, a circuit is closed from ground through the upper right contacts of said key, conductor 318, thence in parallel 70 through the winding of relay 319 and through the lower contact of relay 301, lower front contact of relay 302, conductor 332, lower front contacts of relays 400 and 408, lower contact of relay 417, winding of relay 418 to battery. Relay 418 operates and closes a series circuit for itself and the winding of relay 301 but the latter relay does not operate for the reason explained. Another circuit is traceable from ground 75 through the lower right contact of key 317, conductor 321, conductor 322, winding of relay 323 to battery. Relay 323 locks to the grounded conductor 324. Still another circuit is closed from ground through the left 80 contacts of key 317, conductor 338, winding of relay 339 to battery. Relay 339 locks to the grounded conductor 324.

As soon as relay 418 operates, a circuit is closed from the grounded conductor 324 85 through the contacts of relay 334, conductor 333, middle right contact of relay 418, winding of register relay 421 to battery. Another circuit is closed from the grounded conductor 324 through the contact of relay 339, conductor 338, outermost right contact of relay 418, winding of relay 423 to battery. Relays 421 and 423 lock in circuits through their inner left contacts to the grounded conductor 427. 90

Relay 421 closes a circuit from battery through the winding of relay 417, conductor 435, outer left contact of relay 421, conductor 324, to ground at the upper contact of relay 301. Relay 417 opens the shunt around the winding of relay 301 and this latter relay becomes energized. Relay 301 opens the holding circuits of relays 323, 339, 319, 301, 417 and 418 and these relays all become deenergized. 100

At the time the switch 500 operates to extend the connecting circuit 108 from the operator's position over the idle trunk 509 to the distant mechanical office, a circuit is closed for the relay 603. This circuit leads from battery through the right-hand winding of said relay, lower left-hand winding of repeating coil 606, contact 605 (1+2) of sequence switch 610, ring conductor of the trunk through contacts of the switch 500 to the ring conductor 130, inner left front contact of relay 119, inner upper back contact of relay 122, conductor 136, outer right contact of relay 200, right-hand winding of relay 201 to ground. Another circuit is traceable from ground through the left-hand winding of relay 603, upper left winding of repeating coil 606, contact 604 (1+2), thence over the tip conductor through the contacts of switch 500 to tip conductor 129, outer left 115 conductor 130. 120

front contact of relay 119, uppermost back contact of relay 122, conductor 135, inner right contact of relay 200, left-hand winding of relay 201 to battery. Relay 201 operates in this circuit and closes a circuit from battery through the winding of relay 204, front contact of relay 201, contact of relay 202 to ground through the contact of relay 203. Relay 204 operates and locks 10 through its right contact to ground at the contact of relay 203.

Relay 603 also operates in the circuit traced and completes a circuit from ground through its contact, contact 611 (1), winding of sequence switch magnet 610 to battery. Sequence switch 610 is energized in this circuit and moves out of position 1 and into position 2. As the sequence switch 610 passes through position 1½ it closes at its 20 contact 609 a temporary circuit for the slow-to-release relay 608. Relay 608 operates and remains operated provided the sender selector switch 602 has its brushes on the terminals of a busy sender at this time. The 25 holding circuit for relay 608 may be traced from battery through its winding, contact 652 (2), conductor 634, brush 616 and the terminal on which it is standing, thence through the multiplied terminal of some 30 other sender selector switch and through the corresponding brush 616 thereof, to ground at the contact 607 of the particular sequence switch 610 associated with said other sender selector switch. The contact 607 of the 35 sequence switch associated with the sender selector which is rendering the register sender busy will be in some position between positions 4 and 18. Relay 635 is also energized in parallel with relay 608 over conductor 634, brush 616 to the grounded busy test terminal. With sequence switch 610 in position 2 and relay 635 energized, a circuit is completed from battery through the winding and contact of the sender selector 40 stepping magnet 614 through the contact 613 closed in position 2, to ground at the contact of relay 635. Magnet 614 interrupts its circuit and advances brushes 615 to 618, inclusive, from position to position to search 45 for an idle register sender. Assuming the sender shown in the drawing is idle at this time, no ground potential exists on the terminal encountered by brush 616 and consequently the circuit of relays 635 and 608 is 50 opened. Relay 635 releases immediately and opens the circuit of stepping magnet 614 to prevent further advance of the switch 602. After an interval relay 608 releases and a circuit is closed from ground through 55 the contact of said relay, contact 612 closed in positions 2 and 3, winding of sequence switch magnet 610 to battery. Sequence switch 610 advances its contacts from position 2 through position 3 and into position 60 65 4. With sequence switch 610 in position 4,

ground potential is applied by way of contact 607 to the multiplied terminals with which the brushes 616 of all sender selector switches cooperate to identify this particular sender as busy.

When sequence switch 610 passes out of position 2, it opens at contacts 604 and 605 the circuit previously traced for relay 201 in the manual office. Relay 201 releases and a circuit is completed from battery through the winding of the start relay 200, outer left contact of relay 204, back contact of relay 201, contact of relay 202 to ground at the contact of relay 203. Relay 200 operates and locks through its inner left contact to ground at the contact of relay 203. With relay 200 operated, a circuit is closed for relay 207 as follows, provided relay 302 has been energized: battery, through the winding of relay 207, conductor 220, lowermost contact of relay 309, uppermost contact of relay 302, conductor 340, to ground at the inner left contact of relay 204.

The apparatus is now in condition for transmitting code impulses over the line circuit in the distant mechanical office for setting the register sender shown in Figs. 6 and 7. The code impulses are sent to the indicator mechanism over a full metallic circuit comprising both the tip and ring sides of the line in series. These impulses may be of either positive or negative polarity dependent upon the pole of battery that is connected to a given side of the line circuit. They may also be weak or strong dependent upon whether high or low resistance is included in the circuit. Relay 620 at the distant end of the impulse circuit is polarized in such a manner as to respond only when current of positive polarity flows over the ring side of the line; that is, over the conductor 636. The relay 621 is polarized in such a manner as to respond to current of the opposite polarity. Both relays 620 and 621 respond either to strong or weak impulses provided the polarity is in the proper direction. The relay 619 responds to strong impulses of either polarity but does not respond to weak impulses.

Relays 208 and 209 at the manual office cooperate with each other to measure intervals of time during which code impulses are produced and propagated over the line circuit to the distant office. Due to the characteristics of these relays they operate and release slowly. Relays 211, 212, 213 and 214 operate in a definite sequence and their function is to measure a sufficient number of periods or code impulses to represent each of the different digits.

Relay 207, in operating, establishes a circuit from ground through the inner left contact of relay 204, outermost left contact of relay 207, inner right contact of relay 213, inner right contact of relay 211, outer right

— contact of relay 212, left back contact of relay 213, left-hand winding of relay 214, left-hand winding of relay 213 to battery. Relay 213 being marginal does not operate in this circuit. Relay 214, however, operates and a circuit is closed from battery through the left-hand winding of relay 213, left-hand winding of relay 214, right-hand winding of relay 213, inner right contact of relay 214, to the grounded conductor 340. Relay 213, however, does not operate since its right-hand winding is shunted by the circuit previously traced. Relay 214 closes a circuit from ground through its outer right contact, conductor 221, contact of relay 311, innermost upper back contact of relay 309 winding of relay 308 to battery. Relay 308 operates and closes a circuit from battery through its winding and contact, winding of relay 311, thence to ground over conductor 221. Relay 311, however, does not operate since its winding is shunted by the circuit originally traced for relay 308. Relay 308 at its right-hand armatures connects the thousands register 310 to the impulse circuit in Fig. 2 for determining the transmission of the thousands digit.

Relay 207 also closes a circuit from battery through the resistance 215, winding of relay 208, left back contact of relay 209, conductor 222, conductor 223, innermost left contact of relay 207 to ground at the outer left contact of relay 200. Relay 208 energizes after an interval and closes a circuit from battery through the resistance 216, winding of relay 209, inner left contact of relay 208, to the grounded conductor 222. Relay 209 operates after an interval and closes a circuit from battery through the winding of relay 210, inner left normal contact of said relay, outermost right front contact of relay 209 to ground over conductor 222. Relay 210 operates and locks through its innermost left armature to the grounded conductor 223. Immediately that relay 209 operates, it closes a circuit from battery through the resistance 215, middle right contact of relay 209, to ground over conductor 222. This circuit shunts the relay 208 which releases after an interval.

When relay 208 becomes released it closes a circuit from battery through the resistance 216, right back contact of relay 208 to ground over conductor 222. This circuit shunts the relay 209 which releases its armatures after an interval. While relays 208 and 209 are releasing an impulse is transmitted over the line to the distant mechanical office. The circuit for this impulse may be traced from ground over the positive pole of battery, through the outer right contact of relay 210, middle left contact of relay 207, conductor 225, thence through the normal contact at the middle right-hand armature of relay 205, conductor 136 and thence

over the ring side of the line as previously traced through the sequence switch contact 605 closed in position 4, conductor 636, brush 618, windings of relays 620, 621 and 619 in series, brush 617, conductor 637, contact 604 and thence returning over the tip side of the line to conductor 135, inner normal contact of relay 205, conductor 226, left back contact of relay 212, conductor 227, outer right contact of relay 207, conductor 228, uppermost back contact of relay 309, right contact of relay 304, conductor 342, high resistance 312 to the negative pole of battery. Due to the high resistance 312, the impulse is weak in character. Consequently, the marginal relay 619 does not respond. Due to the polarity of the impulse circuit, the polarized relay 620 responds. Relay 620 operates and closes a circuit from ground through the contact of relay 639, contact of relay 620, left back contact of relay 623, left back contact of relay 624, conductor 640, left-hand winding of register relay 708 to battery.

It will be noted that the relay 639 is operated as soon as sequence switch 610 moves into position 4 after the idle register sender has been seized. The operating circuit of this relay is traceable from battery through its winding, brush 616, conductor 634, contacts 652 and 607, closed in positions 4 to 18 to ground.

Relay 708 operates and locks in a circuit through both its windings and inner right contact, conductors 704, 705 and 706 to ground at the contact of relay 639.

When relay 209 finally releases a circuit is closed from battery through the resistance 206, winding of relay 205, outer left contact of relay 208, innermost right contact of relay 209, inner right contact of relay 210 to ground over conductor 223. Relay 205 operates and opens the impulse circuit to interrupt the impulse being transmitted over the line. Relay 205 locks through its left contact to ground over conductor 222. When the impulse circuit is interrupted, relay 620 at the mechanical office becomes deenergized.

Relay 209 in releasing also completes a circuit from ground over conductor 222, through the outer right back contact of relay 209, outermost left contact of relay 210, conductor 229, left back contact of relay 211, left-hand winding of relay 212, left-hand winding of relay 211 to battery. Relay 212 operates in this circuit, but relay 211 being marginal does not receive sufficient current to attract its armatures. Relay 212 completes a circuit from battery through the left-hand windings of relays 211 and 212 in series through the right-hand winding of relay 211, inner right contact of relay 212 to the grounded battery 340. Relay 211, however, does not operate in this circuit since

its right-hand winding is shunted due to the ground potential on conductor 229. Relay 212 at its outer right contact opens the shunt around the right-hand winding of relay 213 and this relay operates in series with relay 214.

When relay 213 operates, a circuit is closed from ground through the contact of relay 203, contact of relay 202, conductor 230, outer right contact of relay 213, conductor 231, inner right-hand contact of relay 308, winding of relay 309 to battery. Relay 309 operates and locks through its inner lower contact to the grounded conductor 330. Relay 309 opens the shunt around the winding of relay 311 and this latter relay operates in series with relay 308 in the circuit previously traced.

The next period for the transmission of an impulse is determined by the interval required for the relays 208 and 209 to reoperate. Immediately that relay 209 releases, the energizing circuit previously traced is closed for relay 208 and this relay operates after an interval. As soon as relay 208 operates it closes the circuit for relay 209 and this relay also becomes energized. During the interval required for the operation of relays 208 and 209, an impulse circuit is closed from the positive pole of battery through the outer right contact of relay 210, middle left contact of relay 207, conductor 225, innermost right front contact of relay 205, thence over the tip side of the line to the windings of relays 619, 620 and 621 and returning over the ring side of the line through the middle right front contact of relay 205, conductor 232, high resistance 312 to the negative pole of battery. Due to the character of this impulse only the relay 621 is operated. Relay 621 completes a circuit from ground over conductor 706, contact of relay 621, conductor 641, left back contact of relay 622, left-hand windings of relays 623 and 622 in series to battery. Relay 622 being marginal does not operate, but relay 623 attracts its armatures. Relay 623 closes a circuit from battery through the left-hand windings of relays 622 and 623 through the right-hand winding of relay 622, inner right contact of relay 623 to the grounded conductor 706. Relay 622, however, remains deenergized since its right-hand winding is shunted due to the presence of ground on conductor 641. Relay 623 closes a circuit from ground on conductor 706, through the outer right-hand contact of relay 622, left back contact of relay 625, winding of relay 624 to battery. Relay 624 operates and closes a circuit from battery through its winding and the winding of relay 625, inner right contact of relay 624, conductor 642, conductor 706 to ground. Relay 624 operates but relay 625 being shunted remains inert.

When relay 209 operates, it removes ground from conductor 229 whereupon relay 211 operates in series with relay 212 in the circuit previously described. Also, when relay 209 operates it closes a circuit from battery through resistance 206, conductor 233, middle left contact of relay 210, outermost right front contact of relay 209 to the grounded conductor 222. This circuit shunts the relay 205 which releases its armatures and interrupts the impulse being transmitted over the line.

Relay 621 on releasing removes ground potential from the conductor 641 whereupon the relay 622 operates in series with relay 623.

The next period for the transmission of an impulse is measured by the deenergization of relays 208 and 209 which takes place in the manner previously described. During the interval that these relays are undergoing release, a path is traceable from positive battery over conductor 225, thence through the middle normal contact of relay 205, over the ring side of the line and returning over the tip side through the normal contacts of relay 205, conductor 226, left front contact of relay 212, conductor 234, through the next to the outer contact of relay 308 to the armature of relay 306. Since relay 306 is not operated, the impulse circuit is held open at this point and no impulse is transmitted over the line during this period. When relay 209 finally releases, it closes a circuit from ground over conductor 222, outermost right contact of relay 209, outermost left contact of relay 210, conductor 229, left front contact of relay 211, left-hand winding of relay 211 to battery. Relay 211 remains energized in this circuit, but relay 212 being shunted releases its armatures. Relay 209 also opens the shunt around relay 205 and this latter relay operates to prepare the line circuit for the next impulse period.

Relays 208 and 209 now become energized in succession and during the interval required for their energization an impulse is transmitted over the line. A circuit for this impulse leads from the positive pole of battery over conductor 225, thence as previously traced over the tip side of the line and returning over the ring side of the line through the middle front contact of relay 205, conductor 232, high resistance 312 to battery. Due to the character of this impulse only the relay 621 is operated. Relay 621 applies ground potential to conductor 641 whereby relay 622 is held energized but relay 623 being shunted releases its armatures. Upon the release of relay 623 the shunt around the winding of relay 625 is maintained through the inner right contact of relay 622. When relay 209 finally energizes it opens the holding circuit for relay 211 and this relay releases. A circuit is now

closed from battery through the left-hand winding and left front contact of relay 213, outer right contact of relay 212, inner right contact of relay 211, inner right front contact of relay 213, inner right front contact of relay 214 to the grounded conductor 340. Relay 214 is shunted by this circuit and releases its armatures. Relay 214 on releasing opens the holding circuit of relay 213 and 10 said latter relay also deenergizes. Relay 209 in operating also closes the shunt around the winding of relay 205 and this latter relay retracts its armatures to interrupt the impulse being transmitted to the 15 line.

When the impulse is interrupted relay 621 releases and opens the holding circuit of relay 622. Relay 622 releases and removing the shunt around relay 625 permits 20 this latter relay to operate in series with relay 625.

Relay 214 in releasing removes ground from conductor 221 whereupon relays 311 and 308 become deenergized. Relay 308 25 associates the register 310 from the impulse circuit of Fig. 2.

With relays 211, 212, 213 and 214 released, the circuit originally traced is completed for the left-hand windings of relays 213 and 214. Relay 214 operates but relay 213 remains deenergized, being shunted. Relay 214 completes a circuit from ground through its outer right contact, conductor 221, contact of relay 311, innermost upper 30 front contact of relay 309, innermost upper back contact of relay 406, winding of relay 407 to battery. Relay 407 operates and closes a circuit from battery through its winding and left contact, conductor 438, 35 winding of relay 311, thence to ground over conductor 221. Relay 311, however, remains shunted until relay 406 is operated. Relay 407 associates the hundreds register 410 with the impulse circuit.

40 During the next period relays 208 and 209 undergo deenergization but since relay 402 of the hundreds register is deenergized no impulse is transmitted over the line. When relay 209 releases relay 212 becomes operated, relay 213 operates in series with relay 214 and relay 205 energizes in the manner already fully explained. Relay 213 closes a circuit from ground on conductor 230 through its outer right contact, conductor 231, innermost right contact of relay 407, 45 winding of relay 406 to battery. Relay 406 operates and locks to ground over conductors 427 and 330. Relay 406 opens the shunt around relay 311, which operates in series with relay 407 in the circuit traced.

50 During the next period relays 208 and 209 undergo energization and an impulse is transmitted over the line to the distant office. The circuit for this impulse leads from the positive pole of battery over con-

ductor 225, innermost right contact of relay 205, over the tip side of the line and returning over the ring side of the line to the middle right contact of relay 205, outer right contact of relay 205, conductor 235, 70 outer right back contact of relay 211, conductor 236, next to the inner right contact of relay 407, left contact of relay 403, conductor 439, low resistance 313 to battery. Due to the character of this impulse both 75 relays 619 and 621 are operated. Relay 621 closes a circuit hereinbefore traced for relays 622 and 623 and relay 623 operates, relay 622 remaining inert. Another circuit is closed from ground at the contact of relay 639, through the contact of relay 619, outer right back contact of relay 622, inner right front contact of relay 625, inner right back contact of relay 627, conductor 643, left-hand winding of relay 709 to battery. Relay 709 operates and locks to the grounded conductor 704. Relay 623 in energizing completes a circuit from ground over conductor 706, outer right contact of relay 623, left front contact of relay 625, left back contact of relay 627, winding of relay 626 90 to battery. Relay 626 operates and closes a circuit through its winding and the winding of relay 627, through the inner right contact of relay 626 to the grounded conductor 642. Relay 627 being shunted, however, does not operate.

When relay 209 becomes energized at the end of the period ground is removed from conductor 229 and relay 211 operates as explained. Also, relay 205 is shunted and releases. Relay 205 opens the impulse circuit whereupon relays 619 and 621 become deenergized. Relay 621 removes ground from conductor 641 and relay 622 operates in series with relay 623. 100

Relays 208 and 209 become deenergized next, but during the interval required for their release no impulse is transmitted over the line. When relay 209 finally releases, relay 212 becomes deenergized and relay 205 110 operates as already described.

The next and last interval is measured by the energization of relays 208 and 209. During this time an impulse circuit is closed 115 from positive battery over conductor 225, through the inner right front contact of relay 205, over the tip side of the line returning over the ring side of the line, through the middle right front contact of relay 205, conductor 232, through the high resistance 312 to the opposite pole of battery. Due to the resistance 312, a weak impulse is transmitted whereupon only the relay 621 is operated. Relay 621 connects ground potential 120 to conductor 641 and relay 623 is shunted out.

When relay 209 becomes energized, relays 211, 213, 214 and 215 are all deenergized in the manner hereinbefore explained. Relay 130

205 opens the impulse circuit and relay 621 becomes deenergized to open the circuit of relay 622. Relay 622 removes the shunt from around the winding of relay 627 and 5 this relay operates in series with relay 626. Relay 214, on releasing, opens the holding circuit of relay 407 and relay 311. Relay 407 disconnects the hundreds register 410. Relay 214 is immediately operated again in 10 the manner explained, while relay 213 being shunted remains deenergized. Relay 214 in operating connects ground potential to conductor 221 and a circuit is extended there-over through the contact of relay 311, inner 15 upper front contacts of relays 309 and 406, inner upper back contact of relay 416, winding of relay 415 to battery. Relay 415 operates and closes a circuit through its winding and contact, conductor 438, through the 20 winding of relay 311 to ground on conductor 221. Relay 415 operates and associates the tens register 420, but relay 311 remains inert. Relays 208 and 209 undergo deenergization at which time relays 212, 213 and 205 25 are operated. Relay 213 in energizing closes a circuit from ground over conductor 230, through the outer right contact of relay 213, conductor 231, innermost left contact of relay 415, winding of relay 416 to battery. 30 Relay 416 operates and locks to the grounded conductor 427. Relay 416 opens the shunt around the winding of relay 311 and this latter relay operates in series with relay 415.

35 Next the relays 208 and 209 become energized and during the period of their energization, a circuit is closed from ground over conductor 225, through the inner right contact of relay 205, over the tip side of the 40 line, returning over the ring side of the line, through the middle contact of relay 205, conductor 232, through the high resistance 312 to battery. Due to the character of this impulse only the relay 621 is operated. Relay 45 621 in the manner already explained causes the energization of relay 623. Relay 623 completes a circuit from the grounded conductor 706, through the upper right contact of relay 623, the left front contacts of relays 50 625 and 627, left back contact of relay 629, winding of relay 628 to battery. Relay 628 operates and closes a series circuit for itself and relay 629, but relay 629 remains shunted.

55 When relay 209 becomes energized, relay 211 operates and relay 205 releases. Relay 205 opens the impulse circuit and causes the release of relay 621. Relay 621 causes the energization of relay 622.

60 Relays 208 and 209 become deenergized during which time an impulse circuit is closed from positive pole of battery, over conductor 225, thence over the ring side of the line and returning over the tip side of the line by way of conductor 226, left front 65 contact of relay 212, conductor 234, next to

the outer right contact of relay 415, outer right contact of relay 413, conductor 342, resistance 312 to the opposite pole of battery. This impulse causes the operation of relay 620. Relay 620 closes a circuit from ground 70 through the contact of relay 629, contact of relay 620, left front contact of relay 623, outer right front contacts of relays 624, 626 and 628, left back contact of relay 630, conductor 645, left-hand winding of relay 710 75 to battery. Relay 710 operates and locks to the grounded conductor 706.

When relay 209 becomes released it causes the deenergization of relay 212 and the operation of relay 205. Relay 205 opens the impulse circuit and relay 620 releases. Next the relays 208 and 209 become energized and during this period an impulse circuit is closed from positive battery over conductor 225, thence over the tip side of the line and returning over the ring side of the line, through conductor 232, resistance 312 to the opposite pole of battery. Due to the character of this impulse, only the relay 621 responds. Relay 621 in the manner explained causes the release of relay 623. When relay 209 finally operates relays 211, 214, 213 and 205 become deenergized. Relay 205 opens the impulse circuit and relay 621 releases. Relay 621 opens the holding circuit of relay 622, whereupon relay 629 operates in series with relay 628 as already explained. Relay 214, in releasing, opens the holding circuit of relays 311 and 415. Immediately thereafter relay 214 is again operated in a circuit including the left-hand winding of relay 213, but relay 213 remains deenergized as above explained. Relay 214 closes a circuit from ground over conductor 221, contact of relay 311, thence through contacts of relays 309, 406 and 416 and through the lowermost back contact of relay 424, winding of relay 425 to battery. Relay 425 operates, closes a circuit through its winding and contact and the winding of relay 311 to ground over conductor 221. Relay 311 being shunted does not operate at this time. Relays 208 and 209 next become deenergized and during this interval an impulse circuit is closed from positive pole of battery over conductor 225, thence over the ring side of the line, returning over the tip side of the line, through conductor 226, left back 110 contact of relay 212, conductor 227, outer right contact of relay 207, conductor 228, uppermost front contacts of relays 309, 406 and 416, upper back contact of relay 424, right contact of relay 419, conductor 342, high resistance 312 to battery. Due to this impulse relay 620 is operated. Relay 620 115 closes a circuit from ground, through its contact, left back contact of relay 623, left front contacts of relays 624, 626 and 628, conductor 646, left-hand winding of relay 711 to battery. Relay 711 operates and locks 120

125

130

through its windings to the grounded conductor 706.

When relay 209 releases, relays 212, 213 and 205 are energized. When relay 213 operates, it closes a circuit from ground over conductor 230, through its outer right contact, thence over conductor 231, through the innermost right contact of relay 425, winding of relay 424 to battery. Relay 424 operates and locks to the grounded conductor 427. Relay 424 opens the shunts around the winding of relay 311 and this relay operates in series with relay 425. Relay 205 interrupts the impulses and causes the release of relay 620.

Next the relays 208 and 209 undergo energization during which time an impulse is transmitted from the positive pole of battery, over conductor 225, thence over the tip 20 of the line and returning over the ring side of the line, through conductor 232 and resistance 312 to battery. Due to this impulse the relay 621 alone operates and in so doing closes a circuit for the operation of relay 25 623. Relay 623 closes a circuit from ground, over conductor 706, through the outer right contact of relay 623, thence through the left front contacts of relays 625, 627 and 629, left back contact of relay 631, winding of 30 relay 630 to battery. Relay 630 operates and closes a circuit for itself and relay 631, but this latter relay being shunted does not operate. When relay 209 becomes energized it causes the energization of relay 211 and the 35 release of relay 205. Relay 205 opens the impulse circuit and causes the deenergization of relay 621, whereupon relay 622 operates.

Relays 208 and 209 next become deenergized and as soon as this happens relay 212 releases and relay 205 operates. Next, relays 208 and 209 operate and during the interval of their energization an impulse circuit is closed from positive pole of battery, over conductor 225, thence over the tip side of the 40 line and returning over the ring side of the line, through the middle right front contact of relay 205, outer right contact of relay 425, conductor 235, outer right front contact of relay 211, conductor 238, outermost right contact of relay 425, right contact of relay 423, conductor 439, low resistance 313 to the opposite pole of battery. Due to the low resistance 313, relay 619 operates in addition to 45 relay 621. Relay 621 causes the release of relay 623 in the manner described and relay 619 closes the circuit from ground through its contact, outer right front contact of relay 622, outer right front contacts of relays 50 625, 627 and 629, conductor 648, right-hand winding of relay 712 to battery. Relay 712 operates, locks to the grounded conductor 706. When relay 209 finally becomes energized it causes the release of relays 211, 214, 213 and 55 205.

Relay 205 in releasing opens the impulse circuit and relays 619 and 621 become deenergized. Relay 621 opens the holding circuit of relay 622 and this relay releases to remove the shunt from around the winding of relay 631. Relay 631 thereupon operates in series with relay 630 and locks to the grounded conductor 632.

A release of the register sender at the operator's position will now be described. As 75 soon as relay 214 releases, it opens the holding circuit of relays 311 and 425 and these relays become deenergized. Immediately thereafter the relay 214 operates in the manner previously described. Relay 214 now 80 closes a circuit from ground through its outer right contact, conductor 221, contact of relay 311, innermost upper front contacts of relays 309, 406 and 416, lowermost front contact of relay 424, conductor 440, winding 85 of release relay 203 to battery. Relay 203 operates and removes ground from conductor 230 whereupon all energized relays are immediately released and the sender is restored to its normal condition. 90

Relay 203 in operating also opens the holding circuit of relay 119. Relay 119 releases, disconnecting the sender from the connecting circuit 108 and completing said circuit 108 for conversation. 95

With the record of the called line number established on the numerical registers in Fig. 7, the sender may exercise control over the selective switches 600 and 601 illustrated diagrammatically to extend the incoming 100 trunk through to the called subscriber's line 633. Although the register sender is not fully shown in all its details, it will be understood that the registers 700, 701 and 703 after taking their settings corresponding to 105 the digits of the numbers may determine the operation in any well-known manner of a set of counting relays or other similar device for measuring the amount of movement taken by the selector switches 600 and 601. The small circles including the different digits from 0 to 9 shown in connection with the registers indicate points from which multiple taps may be made in the usual manner to the counting relay set. 110

After a sender has received its record and is ready to exercise control over the first selective switch 600, a condition is brought about as by the advance of a sequence or controlling switch (not shown) whereupon a contact 656 is closed to establish a circuit through brush 615, contact 650, winding of sequence switch 610 to battery. Sequence switch 610 moves out of position 4 and into some position beyond where the first selective movement of the switch 600 is made. For a more complete description of a register sender of the same general type of the one illustrated in Figs. 6 and 7 wherein registers of the relay type determine the opera- 115 120 125 130

tion of counting relays to in turn determine the selective movement of switches, reference is made to the patent to Lundell and Stearn, 1,345,016 granted June 29, 1920.

- 5 After the conversation has been completed, the subscribers replace their receivers on the switchhooks and the operator at the position shown in Fig. 1 receives the usual disconnect signals. She removes the plugs 104 and 106 from the respective jacks whereupon relays 107 and 121 become deenergized. Relay 121 opens the holding circuit of relay 120 and also the holding circuit of the horizontal magnet 512 and relays 523 and 522. 10 Magnet 512 restores the associated rod and the connection through the switch 500 is released. The release of the switch 500 and the disconnection from the outgoing trunk 509 may bring about the release of switches 15 600 and 601 in any well known manner.

It will be assumed next that the operator at position 105 receives a call for the distant mechanical office illustrated at a time when all of the connecting circuits 108 and 109 20 at her position representing this office are busy. The operator on finding that the circuit 115 at the adjacent operator's position 110, which represents the same called office, is idle, she may appropriate this circuit for 25 use by inserting the overflow plug 118 in the overflow jack 117 of said circuit 115. The insertion of the plug 118 in jack 117 closes a circuit from battery through the winding of relay 128, through the sleeve of 30 the jack and plug, thence over conductor 137, winding of relay 202, contact of relay 203 to ground. Relay 128 operates and disconnects the conductors 140, 141 and 142 which lead to the sender associated with the 35 adjacent operator's position 110. In this manner, the circuit 115 is rendered non-connectable to the adjacent operator's sender, and is connected instead through the overflow plug and jack to the conductors 40 135, 136 and 137 leading to the sender at the position 105. Next the operator at position 105 inserts the plug 106 of her regular cord circuit in the regular jack 116 of the 45 connecting circuit 115 which she has appropriated for use. The insertion of plug 106 in jack 116 causes the operation of the switch 500 or another switch similar thereto in exactly the same manner as described in 50 connection with the first call. The operator 55 now sets up a number on her keyboard and thereafter the register sender transmits code impulses to record the record of an idle sender in the distant mechanical office. After the connection has been completed 60 and conversation is over the equipment is released by the operator removing the plugs of her cord circuit from the respective jacks.

65 Although the distant office is described herein as a mechanical office wherein selec-

tive switches are employed for further extending the connection, it will be understood that the record may be received on an indicating mechanism and the number corresponding displayed before an operator 70 and the operator may complete the connection manually.

What is claimed is:

1. The combination with an operator's 75 position, of a number of conversational circuits terminating in said position, means under the control of the operator for making connection with said circuits, a group of trunks, a switch responsive to the act of the operator in making connection with one of said circuits for connecting such circuit to one of said trunks, a selective switch for further extending said trunk, a register sender comprising a plurality of registers for storing designations, means responsive 80 to the act of the operator in making connection with one of said circuits for connecting the register sender to such circuit, and means controlled by the sender for governing the operation of said selective switch. 90

2. The combination with an operator's 95 position of a number of conversational circuits terminating in jacks at the operator's position, plug-ended cord circuits at said position, a group of trunks, a switch responsive to the insertion of a plug in the jack of one of said conversational circuits for connecting said circuit to one of said trunks, a selective switch for further extending said trunk, a register sender for storing designations at the operator's position, means responsive to the insertion of the plug in the jack of said connecting circuit for connecting the register sender to such circuit, and means controlled by the sender for governing the operation of said selective switch. 100

3. The combination with an operator's 110 position of a plurality of connecting circuits outgoing therefrom, a group of trunks, and a cross-bar switch responsive to the act of the operator in making connection to any one of said connecting circuits for connecting such circuit to one of said trunks.

4. The combination with an operator's 115 position of a plurality of conversational circuits terminating in jacks thereat, plug-ended cord circuits at the operator's position, a group of trunks, and a cross-bar switch having links, said switch being responsive to the insertion of any number of 120 said plugs in the jacks of different conversational circuits for establishing co-existing connections between such conversational circuits and said trunks.

5. The combination with a plurality of 125 operators' positions of conversational circuits outgoing from each position, a group of trunks, a sender at each position, means when the operator at any position makes connection with one of the conversational 130

circuits for connecting her sender to such circuit and for connecting the circuit to one of said trunks, selective switches for further extending said trunks, and means controlled by said senders for governing the operation of said selective switches.

6. The combination of a plurality of operators' positions of a number of distant offices, a switch individual to each of said 10 distant offices, a group of connecting circuits leading from each position to each of said switches, trunks outgoing from each switch to the corresponding distant offices, a sender at each position, means responsive to the act on the part of an operator in making connections to one of said connecting circuits for connecting her sender thereto and for operating the corresponding switch to extend such connecting circuit to one of said 20 trunks, selective switches at the distant end of said trunks, and means controlled by said senders for governing the operation of said selective switches.

7. In a telephone system a plurality of operators' positions, plug-ended cord circuits at said positions, circuits outgoing from each position, each outgoing circuit appearing in a regular jack and in an overflow jack at the position, a sender at each position, means responsive to the insertion of a plug in a regular jack at a given position for connecting the sender at such position to the corresponding circuit, an overflow plug at each position, and means responsive to the insertion of the overflow plug at a given position in the overflow jack of a circuit at another position for connecting the sender

at said given position to said last mentioned circuit and for rendering such circuit non-connectable to the sender at said other position.

8. In a telephone system, an operator's position, trunks outgoing therefrom, a register sender at said position, means responsive to the act of the operator in making 45 connection to one of said trunks for connecting the sender to such trunk, selective switches at the distant end of said trunks, a second register sender associated with said selective switches, means controlled by said 50 first sender for establishing a designation record in said second sender, and means controlled by said second sender for operating said selective switches.

9. In a telephone system, an operator's 55 position, trunks outgoing therefrom, a register controlling sender at said position, means responsive to the act of the operator in making connection to one of said trunks for connecting the sender to such trunk, 60 selective switches at the distant end of said trunks, a second register sender associated with said selective switches and connectible to any one of said trunks, means controlled by said first sender for transmitting code 65 impulses over said trunks to establish a designation record in said second sender, and means controlled by the second sender in accordance with said record for setting 70 said selective switches.

In witness whereof, I hereunto subscribe my name this 4th day of December, A. D. 1922.

SAMUEL B. WILLIAMS.
